UNITED STATES PATENT OFFICE.

EMIL E. HONSEBERG, OF WASHINGTON, DISTRICT OF COLUMBIA.

RECOIL AND COUNTER-RECOIL BRAKE FOR GUNS.

1,411,627.

Specification of Letters Patent. Patented Apr. 4, 1922.

Application filed August 26, 1921. Serial No. 495,449.

To all whom it may concern:

Be it known that I, EMIL E. HONSEBERG, a citizen of the United States, residing at 1905 15th Street Northwest, in the city of 5 Washington and District of Columbia, have invented certain new and useful Improvements in Recoil and Counter-Recoil Brakes for Guns; and I do hereby declare the following to be a full, clear, and exact description of the invention, such as will enable others skilled in the art to which it appertains to make and use the same.

The invention relates to a novel and useful hydraulic brake for heavy ordnance or artillery, and has for its object a simple and effective device of the character indicated, involving but few parts or elements and operating with certainty and definiteness not only in taking care of the recoil when the 20 gun is fired, but also serving as a highly efficient check or brake for the counter recoil. To these ends the invention comprises a cylinder formed with, or secured to the cradle, or to the gun, having a length slightly 25 more than twice the length of the normal recoil of the gun, in which works a piston rod, connected at one end to a lug on the breech end of the gun, or to the cradle or other stationary part of the mount, said 30 rod being provided with two spaced pistons, one of which is solid, and serves as a brake or check for the recoil, and the other of which is provided with a port or passage, with which cooperates a check valve, which 35 port is freely opened during the recoil stroke of the device and is closed by said check valve during the counter recoil stroke of said device, the interior of the brake cylinder preferably being provided with longitudinal 40 grooves which taper from each end toward the mid section of the cylinder, where they are deepest, which grooves provide for the gradual escape of the fluid in the cylinder past the pistons in both the recoil and counter recoil checking operations.

The invention is illustrated in the accompanying drawing, in which the figure is a longitudinal section through the brake mechanism as applied to a heavy gun, the latter 50 being indicated by dotted lines.

Referring to the drawing, 1 indicates the barrel of the gun, the breech end of which is provided with a lug 2, the gun barrel being supported and guided, in its movement 55 during recoil and counter recoil, in a cradle

or slide 3, which is more or less diagrammatically illustrated. Either formed integrally with the cradle 3, or, preferably, supported in a generally tubular bearing in said cradle is a cylinder 4, having a length somewhat in excess of twice the length of the normal recoil of the gun. One end of said cylinder is closed by a cap 5, which may be formed integrally with the cylinder, and is provided with a cylindrical bearing for the 60 rod of the recoil brake, and a suitable gland or stuffing box which is to prevent leakage about the brake rod. The other end of the cylinder 4 is closed by a removable cap 7, which may be secured in position by any 65 suitable means, and forms a fluid tight joint with the cylinder end; said cap 7 is likewise provided with a cylindrical bore, forming a bearing for the brake rod and fitted with a gland or stuffing box 8, as indicated. 70

Slidably mounted in the caps, constituting the closures for the ends of the cylinder 4, is a brake rod, which may be formed of one piece, but which for convenience of manufacture and assemblage comprises two cylindrical sections 9 and 10, connected together within the cylinder by means of a threaded socket joint such as 12. Intermediate the length of section 10 of the rod, there is provided a solid piston 13 which may, if desired, be formed integrally with the rod, and which accurately fits the bore of the cylinder 4, said piston constituting the check or brake for the recoil, in which respect it does not differ materially from the ordinary type 80 of recoil brake or check heretofore employed. The forward end of the rod section 10 is provided with a piston 14, having one or more openings 16 therethrough, surrounded by a tapering rim 15, constituting a valve seat. 85

The end of the rod section 10 in front of the piston 14 is preferably reduced in cross section and has mounted thereon for free sliding movement a check valve 17, which cooperates with the valve seat 15, the outward or opening movement of said valve being limited by the collarlike stem of said valve engaging the end of rod section 9. 95

The piston 14 may be formed as an integral part of the rod section 10, or may be 100 made up as a separate element and secured to said rod section by any suitable means. As a matter of convenience, the piston is formed as an annular rim connected with the rod or hub portion by radial webs or 110

2
fins to leave free passageway through the piston.

It will be understood that the brake cylinder 4 is filled with a suitable fluid such as oil and, when the gun is fired, the barrel 1 runs back in the cradle 3 carrying with it the rod and pistons of the brake mechanism. During the initial part of the recoil the liquid in the cylinder 4 behind the piston 13 escapes freely through the deeper portions of the grooves 20 and as the piston 13 travels rearwardly the gradual decrease in the depth of the grooves 20 exercises a heavy throttling action on the fluid which arrests the movement of the piston and gradually brings the gun barrel to rest. In order to return the gun to battery, it is provided with the usual recuperators, which may be of any appropriate type, and which are not illustrated for this reason. Inasmuch as the modern type of heavy ordnance is designed to be fired at elevations of -7 deg. to 65 deg., it will be appreciated that if the recuperator mechanism is made powerful enough to return the heavy gun and recoiling parts to battery at 65 deg. elevation, there will be a great excess of recuperative power when the gun is at zero degrees or at -7 deg. depression. It was therefore found necessary to devise an automatic brake or buffer that would effectively take up the widely varying energy of the counter recoil and nevertheless permit the gun to be promptly returned to battery without undue shock. During the recoil stroke the check valve 17 cooperating with piston 14 opens and allows the oil in the cylinder to pass freely through the openings in said piston. On counter recoil the valve 17 instantly engages seat 15 in piston 14 and closes the opening 16 through the piston, so that the oil can only escape from the forward portion of the cylinder 4 through the throttling grooves 20 cut in the walls of the cylinder along the path of travel of this piston. The portions of the grooves 20 cooperating with the piston 14 are much smaller in cross sectional area than the portions of the grooves cooperating with the recoil piston 13 so that the movement of the gun on counter recoil is effectively controlled. If the gun is at a high angle of elevation, it moves slowly into battery, as the force returning it to battery is equal to the effective pull of the recuperator minus the component of the weight of the gun in the same direction minus frictional resistances. In this case the pressure developed in the cylinder during counter recoil is small. If, however, the gun is at a low angle of elevation or is actually depressed, when in battery, the recuperator tends to throw the gun into battery at a high velocity since the component of the weight of the gun is small. Therefore, a high pressure is developed in the cylinder

which quickly reduces the velocity of the recoiling parts. The system is thus automatic between wide limits of elevation, and controls the gun so that it will move slowly and smoothly into battery at all angles of elevation. It will be noted that during the major portion of the travel of piston 13 during counter recoil said piston traverses the portions of grooves 20 having the enlarged cross section, so that the oil can escape freely past this piston during the counter recoil and said piston therefore offers very little resistance to the counter recoil which latter, however, is effectively taken care of by piston 14 as described.

Although only one recoil and counter recoil brake is illustrated in connection with the gun, it will be understood that they may be effectively used in pairs, or in any desired number and may also be employed in connection with ordinary counter recoil buffers, or variable recoil systems, but in a large majority of cases the simple form of apparatus as illustrated will be found sufficient and effective to check the movement of the heaviest guns on both recoil and counter recoil. The especial advantages of the brake mechanism, constituting the present invention, are:—The functioning of the recoil brake is entirely separate and independent of that of the counter recoil brake or buffer and said recoil brake may be of the simplest type; the length of control on counter recoil is practically the same as that on recoil, and at the same time, the effective area of the counter recoil buffer is the same as that of the recoil piston thus permitting the employment of low pressures with maximum control; the device avoids the complication inherent in variable counter recoil buffers in which variable resistance is obtained by mechanically varying an orifice to suit the angle of elevation of the gun; the construction and arrangement of the device is exceptionally simple and involves the fewest possible number of correlated parts, none of which is liable to derangement or damage during the normal operation thereof; and finally the construction and arrangement of the brake permits the latter to be applied to the standard gun and its mount without involving any material changes in the latter from standard practice.

It is to be understood that the particular construction and relative arrangement of parts, as illustrated and described, are merely exemplary and may be varied as desired, to conform to standard practice on different types of stationary and mobile ordnance, or to meet special conditions. For example, the recoil cylinder may be secured to the gun barrel so as to move therewith and the brake or piston rod secured to the cradle or other stationary part of the gun mount; also the order of the recoil and coun-

ter recoil pistons may be reversed without changing or varying the proper functioning of the brake as a whole.

The right to use the invention described herein is hereby assigned to the United States Government for its use without the payment of royalty thereon.

What I claim is:—

1. Fluid brake mechanism for guns comprising a brake cylinder, spaced pistons in said cylinder one piston being solid and the other piston having a port therethrough, a rod connecting said pistons and connected to a gun part, a check valve cooperating with the ported piston to open said port during the recoil stroke and close the port during the counter recoil stroke, and means for throttling the flow of the fluid past the pistons.
2. Fluid brake mechanism for guns comprising a brake cylinder, spaced pistons in said cylinder one piston being solid and the other piston having a port therethrough, a rod connecting said pistons and connected to a gun part, a check valve cooperating with said ported piston to open said port during the recoil stroke and close the port during the counter recoil stroke, and grooves in the cylinder wall for throttling the flow of the fluid past the pistons.
3. Fluid brake mechanism for guns comprising a brake cylinder, spaced pistons in said cylinder one piston being solid and the other piston having a port therethrough, a rod connecting said pistons and connected to a gun part, a check valve cooperating with

said ported piston to open said port during the recoil stroke and close the port during the counter recoil stroke, and grooves in the cylinder wall increasing in cross section 40 from the ends of the cylinder towards the middle thereof for throttling the flow of the fluid past the pistons.

4. Fluid brake mechanism for guns comprising a stationary cylinder having throttling grooves formed longitudinally of its inner walls, a rod traversing said cylinder and connected at one end to the breech of the gun, a recoil brake piston on said rod intermediate the ends thereof, a counter recoil buffer piston on said rod near the forward end thereof having a port therethrough, and a check valve cooperating with said buffer piston to open the port during the recoil of the gun and to close said port 55 during counter recoil.

5. Fluid brake mechanism for guns comprising a stationary cylinder, a rod extending through the ends of said cylinder and connected at one end to the breech of the 60 gun, a recoil brake piston on said rod intermediate the ends thereof, a counter recoil buffer piston on said rod spaced forwardly of the recoil piston and having a port therethrough, a check valve slidably mounted on 65 the rod adjacent the forward face of said buffer piston to open said port during the recoil of the gun and to close the port during counter recoil.

In testimony whereof I affix my signature. 70

EMIL E. HONBERG.
